UNITED STATES PATENT OFFICE.

ALBERT CAMERON HUNT, OF NACO, ARIZONA TERRITORY, ASSIGNOR TO
BERNARD JOSEPH O'REILLY, OF NACO, ARIZONA TERRITORY.

GATE.

SPECIFICATION forming part of Letters Patent No. 726,689, dated April 28, 1903.

Application filed September 30, 1902. Serial No. 125,348. (No model.)

To all whom it may concern:

Be it known that I, ALBERT CAMERON HUNT, a citizen of the United States, and a resident of Naco, in the county of Cochise and Territory of Arizona, have invented a new and Improved Gate, of which the following is a full, clear, and exact description.

This invention relates to a gate constructed principally of wire and connected with a swinging frame which holds the wires distended and which has attached to its free portion a device for engaging the post and stretching the wires taut in connection therewith.

15 This specification is an exact description of one example of my invention, while the claims define the actual scope thereof.

Reference is to be had to the accompanying drawings, forming a part of this specification, 20 in which similar characters of reference indicate corresponding parts in all the views.

Figure 1 is a side view of the invention. Fig. 2 is a plan view showing particularly the device for stretching the wires when the gate 25 is closed, and Fig. 3 is a sectional elevation on the line 3-3 of Fig. 1.

20 a indicates the post on which the gate swings, and b indicates the post with which the free end of the gate is adapted to be engaged.

Mounted on the post a to swing around a center at the point a' is a horizontal beam c, which is sustained in its horizontal position by a guy d, attached to a clip c' on the beam 35 and itself swinging on the part a.

e indicates the running-wires, forming the gate proper, and these are connected by the rings e' with the post a, so as to swing on the said post with the beam c.

40 f indicates a lever which is fulcrumed on the free end of the beam c at a point f', said lever having the running-wires e connected therewith at their outer ends.

b' indicates a keeper on the post b, adjacent 45 to the upper end of the lever f, so as to be engaged therewith, and b² indicates a keeper at the bottom of the post below the lower end of said lever.

Fulcrumed to the lever f at the point g' 50 near the bottom of said lever is a lever g, which has its lower end extended below the

lever f in position to engage the keeper b². The upper end of the lever g is projected upward alongside of the beam c, where it is retained by a guide c², extending from the clip 55 c' to the free end of the beam.

c³ indicates a keeper on the free end of the beam c to be engaged by the lever g when said lever is in closed position, as shown by the full lines in Fig. 1.

In order to close the gate, the lower end of the lever g should be engaged with the keeper b² and the upper end of the lever f should be engaged with the keeper b', the levers then occupying the position shown by the dotted 60 lines in Fig. 1. Then by throwing leftward the upper end of the lever g and engaging the same with the keeper c³ the wires e will be rendered taut and the two levers f and g will be held firmly engaged with their respective 65 keepers b' and b². This forms a gate effectively spanning the space between the posts a and b, and said gate cannot be released until the lever g is disengaged from the keeper c³ and thrown again into the position shown 70 by dotted lines in Fig. 1. The wires e being thus slackened, the levers f and g may be entirely disengaged from the keepers and the gate swung, with the beam c, to either side of the post a, thus opening the space between 75 80 the posts.

Various changes in the form, proportions, and minor details of my invention may be resorted to at will without departing from the spirit and scope thereof. Hence I consider 85 myself entitled to all such variations as may lie within the intent of my claims.

Having thus described my invention, I claim as new and desire to secure by Letters Patent—

1. The combination with a support, of a member arranged to swing thereon, a lever fulcrumed on said member, a flexible connection extending between the lever and the support, a second lever fulcrumed on the first 95 lever, keepers mounted independently of the said swinging member and adapted to be engaged respectively by the levers, and an additional keeper on the swinging member and adapted to be engaged by the second-named 100 lever.

2. In a gate, the combination of a stationary

support, a member mounted to swing thereon and extending outward therefrom, a lever fulcrumed on the said member, flexible connections between the lever and said support, a keeper removably engaged by the lever, a second lever fulcrumed on the first lever, a keeper adapted to be removably engaged by the second lever, and a third keeper, the said third keeper being mounted on the swinging member and adapted to be engaged by the second lever, for the purpose specified.

3. In a gate, the combination of a stationary support, a member mounted to swing thereon and extending outward therefrom, a lever fulcrumed on the said member, flexible connections between the lever and the support, a

keeper removably engaged by the lever, a second lever fulcrumed to the first-named lever, a keeper adapted to be removably engaged by the second lever, a third keeper, the third keeper being mounted on the swinging member and adapted to be removably engaged by the second - named lever, and a guide mounted on said swinging member and inclosing the free part of the second-named lever. 25

In testimony whereof I have signed my name to this specification in the presence of two subscribing witnesses.

ALBERT CAMERON HUNT.
